(57) **CLAIM**

The ornamental design for a rear portion of golf club head, as shown and described.

DESCRIPTION

FIG. 1 is a rear elevational view of a first embodiment of a rear portion of a golf club head;

FIG. 2 is a left side view of the embodiment illustrated in FIG. 1, the front elevational view and right side view being unornamented;

FIG. 3 is a rear elevational view of a second embodiment of a rear portion of a golf club head; and,

FIG. 4 is a left side view of the embodiment illustrated in FIG. 3, the front elevational view and right side view being unornamented.

The broken lines shown in the Figures are for illustrative purposes only and form no part of the claimed invention.
